4 Claims. (Cl. 83—698)

In sheet-metal (or plate-cutting) shears it is known to secure the units, each consisting of a blade and its mounting, in the shearing-machine saddles, by means of screw-threaded bolts and nuts. To change the blades, these connections have to be released in each case by hand.

A sheet-metal shearing machine has also already become known, in which, on the ledge of the mounting, shoulders are provided, which can be inserted into slots in the shearing-machine saddle, and can be held fast in the inserted position by a screw-threaded bolt extending in the direction of shearing. This device also requires manual work in fastening and releasing the mounting. The bolt thread is sensitive to contamination and to damage.

The object of this invention is to provide an automatic securing means for the blade units to the lower and upper shearing-machine saddles, so as to shorten the duration of stoppage of the shearing line when changing the blades.

This is attained, according to the invention, by providing, on the shear saddle, hydraulically acting fastening means on both sides of a mounting, which is supported in the direction of the shearing pressure acting perpendicularly upon the blade, and also in the direction of the chewing pressure, which acts horizontally upon the front of the blade. By this arrangement of the fastening means in relation to their direction of action, and by the inclination of the surfaces by which the fastening means engage the mountings, a component of the holding force is provided which is in the same direction as the chewing pressure.

According to a further feature of the invention, cylinders connected with a source of liquid under pressure are horizontally arranged laterally on the upper shearing-machine saddle, the pistons slideable in these cylinders being connected in each case with a set bolt or tension bolt provided with a recess, there being associated with each of these set bolts a shoulder, corresponding to the recess, on the mounting, the recess and the mounting shoulder being correlated with one another, on the scrap-blade side, by an inclined surface.

According to a further feature of the invention, there are guided, in the lower shearing-machine saddle, bolts directed towards the mounting, which are connected with the slideable pistons of cylinders flanged laterally on to the shearing-machine saddle and communicating with a source of pressure liquid. Of these cylinders the one arranged on the scrap-blade side is of smaller cross-sectional area than the opposite one, the bolt ends and the mounting engaging one another by inclined surfaces.

In this way a blade-fastening is provided in which the securing means can be automatically removed from the lifting-out region of the blade units, whereby it is rendered

2

possible to make the entire blade-changing operation automatic.

One constructional example of the invention is illustrated in the accompanying drawings, in which:

5 FIGURE 1 shows part of a sheet-metal shearing machine in sectional elevation, the plane of section being transverse to the blades; and

10 FIGURE 2 shows a plan of the front portion of the shearing machine, with the upper part in section on the line II—II in FIGURE 1, at the level of the upper blade.

In a sheet-metal shearing machine 1, in a recess of 2 of the movable upper shearing-machine saddle 3, is arranged a mounting 4, which is combined into a unit with the main blade 5 and the scrap blade 6. To the shearing-machine saddle 3 are secured cylinder-holders 7 and 7', to which are flanged cylinders 8 and 8', the pistons of which, not shown, are connected with set bolts or tension bolts 9 and 9'. These set bolts are of hook-like construction, and engage over shoulders 11 and 11' on the mounting 4, and hold the latter firmly against the upper shearing-machine saddle 3 when the piston is acted upon by pressure liquid. The shoulder 11' arranged on the scrap-blade side has an inclined surface, against which there acts the set bolt 9', which is equipped with a surface of the same obliquity, so that even in the direction of the chewing pressure of the scrap blade 6 a satisfactory bearing contact with the shearing-machine saddle 3 is obtained.

15 The lower shearing-machine saddle 12 accommodates, in a recess 13, a mounting 14, with the main blade 15 and the scrap blade 16 connected therewith. The mounting 14 has shoulders 17 and 17', each with an inclined surface, upon which a bolt 19 or 19', bevelled at the tip and connected with the piston, not shown, of a cylinder 18 or 18' is pressed by supplying pressure liquid to these pistons.

20 The cylinder 18 is of larger cross-sectional area than the cylinder 18', so that in the direction of the chewing pressure of the scrap blade a greater force becomes operative, and a more reliable bearing of the mounting upon the shearing-machine saddle 12 is ensured.

I claim:

25 1. A device for securing units, each consisting of a shear blade and its mounting, to the upper and lower saddles of a sheet-metal shearing machine, comprising: a mounting supported on the shear saddle in the direction of the shearing pressure and the chewing pressure, and hydraulically actuated securing means provided on the shear saddle at both ends of the said mounting, the co-acting contact surface of the mounting and of the securing means being at such an inclination that the holding force transmitted from the hydraulically actuated securing means to the mounting is not purely axial in direction but includes a component acting in the direction of the horizontal chewing pressure applied to the front of the blade.

30 2. A device as claimed in claim 1, further comprising a scrap blade accommodated in each mounting at an angle to the main blade, the axial component of the holding force being directed towards that surface of the blade beam which takes up the chewing pressure of the scrap blade.

35 3. A device as claimed in claim 2, further comprising: horizontal hydraulic cylinders arranged laterally on the

upper shearing-machine saddle, and bolts actuated by the hydraulic cylinders and adapted to engage the upper mounting, the co-acting surfaces of the bolts and the mounting at the scrap-blade end of the mounting being inclined.

4. A device as claimed in claim 2, further comprising: hydraulic cylinders flanges laterally to the lower shearing machine saddle, and bolts guided in the lower saddle, directed towards the lower mounting, and actuated by the said hydraulic cylinders, the co-acting surfaces of the bolts and the mounting at both ends of the mounting being inclined, and the hydraulic cylinder at the scrap-blade end of the mounting being of smaller cross-sectional area than the one at the other end.
